[57] CLAIM

The ornamental design for a portable nozzle mount for
firefighting nozzle, as shown and described.

DESCRIPTION

FIG. 1 is a perspective view of the portable nozzle
mount for firefighting nozzle design in position of use
and with broken line disclosure shown for illustrative
purposes only;

FIG. 2 is a right-hand elevational view;

FIG. 3 is a front elevational view;

FIG. 4 is a rear elevational view;

FIG. 5 is a top plan view; and

FIG. 6 is a bottom plan view.
